Attorney.

UNITED STATES PATENT OFFICE.

ISIDORO B. CALVETE, OF LONDON, ENGLAND.

CLIP FOR HAIR-WAVING SACHETS.

Application filed November 6, 1926, Serial No. 146,789, and in France January 2, 1926.

When performing the permanent waving of hair, it is necessary after having coiled the tress of hair on a suitable curler to enclose it in a sachet ordinarily made of paper, 5 cellophane, cloth or similar thin material. Said sachet is generally closed at one end and open at its other end adjacent the hair so as to permit the insertion of the tress but provided at said open end with removable 10 stopping means so designed as to provide a hermetic closure such as will prevent any hot gases or vapours evolved inside the sachet to flow and injure the scalp. Various stopping means including clips and clamps have been 15 proposed heretofore for providing such a hermetic closure of the sachet but they are all more or less deficient.

The present invention has for its primary 20 object to provide a clip of improved and efficient structure adapted for permitting to easily and adjustably constringe and close in a strictly hermetic way the open end of hair waving sachets of the type set forth.

A further object of the invention is to 25 provide a clip of the aforesaid type easily operable by hand for permitting the hair dresser at any moment in the course of the waving operation to further constringe the end of the sachet for taking up any leakage 30 due to its contraction under the effect of heat and for thus preventing any appreciable amount of hot gases or vapours to escape out of the sachet.

A still further object of the invention is 35 to provide a clip of the aforesaid type permitting the hair dresser to progressively and securely constringe and close single-handed the end of the sachet step by step whilst precluding any disengagement thereof in the 40 course of the waving operation.

With these and such other objects in view as will incidentally appear hereinafter, the invention consists in the novel construction, arrangement and combination of parts that 45 will now be described.

In the accompanying drawing:—

Figure 1 is an edge view of the improved clip as applied upon the constricted end of a hair waving sachet.

Figure 2 is a front view of the clip showing its companion jaws in open position.

Figure 3 is a similar view to Figure 2 showing the companion jaws of the clip in inverted and closed position.

Figure 4 is a front view of a modified con-

struction of the clip, assuming its companion jaws to be in their partly closed position.

Figure 5 is a similar view to Figure 4 showing the companion jaws of the clip in a wholly closed position, a part of the clip 60 being illustrated in a position different from that of Figure 4.

Like references designate like parts throughout the several views.

1 designates the one jaw of the clip, 2 its 65 companion jaw. These two jaws are advantageously made of thin sheet metal and they are arranged in overlapping relation by their adjacent ends and hingedly connected to each other by a pivot 3 constituted by a pin 70 preferably riveted to a pair of washers or else by a grub screw. Away from the pin 3 each jaw has an arcuate branch so as to delineate with its companion jaw a curvilinear recess B, said recess being continuous 75 so as to encompass and constringe the open end part of the hair waving sachet A. The outer curvature of the branch of the jaw 1 has its centre at 3 and the outer edge of said branch presenting such curvature is 80 formed with ratchet teeth or serrations as at 5. Moreover in the embodiment illustrated in Figures 2 and 3, the thin metal plate of which the jaw 1 is made is folded upon itself at 6 clear of the teeth 5 and at 85 right angles to the plane of said jaw so as to provide a finger piece whereby it is possible to swing said jaw with respect to the pin 3. The companion jaw 2 is formed in its extremity opposite to the pin 3 with a 90 hole for the reception of a pivot pin 7 carrying a channelled rocker having one wing portion angularly cut as a pawl 8 to engage the ratchet teeth or serrations 5. This rocker is constituted by a flat elongated heel 9 the 95 outer face of which acts as a finger rest for both bringing the pawl 8 into engagement with the teeth 5 and for swinging the jaw 2 about the pivot pin 3 whilst the inner face of said heel 9 has formed integral therewith or fixed thereto two substantially parallel wings 10 and 11 having tongue-like extensions 10^a and 11^a the spacing of which is slightly greater than the thickness of the two juxtaposed jaws 1 and 2 whereby the 105 latter may snugly slide between the tongues 10^a and 11^a which thus act as guides for retaining the pawl 8 in engagement with the teeth 5, as long as the rocker is not swung back about its pivot 7, by precluding any 110

sway or lateral distortion of the jaws when the rocker and its jaw 2 are pushed closer to the jaw 1 to constrict the recess B. The wing 10 is bevelled or angularly cut at 8 intermediate the heel 9 and the tongue 10^a to provide the pawl which is adapted to engage the ratchet teeth or serrations 5 and to be arrested in position by one of them so as to determine the area of the recess B in 10 which is constrictly imprisoned the end of the sachet A.

For the sake of constructional simplicity, the wings 10 and 11 depending from the rocker heel 9 may be alike as illustrated. 15 However it will be understood by anyone skilled in the art that only that one wing which is adjacent to the ratchet teeth or serrations 5 might be cut as a pawl 8 and a guiding tongue 10^a; this modification is self-20 explanatory and need not be further described. As will also be readily understood, the angularly cut portion 8 of the wing 10 might instead of being formed as a pawl be arranged to frictionally engage the arcuate 25 edge 5 which could be smooth i. e., deprived of any teeth or serrations whereby the two jaws 1 and 2 could nevertheless be firmly held together so as to invariably delineate the recess B. These modifications are obvious 30 and do not require any illustration.

In the further embodiment illustrated in Figures 4 and 5, the jaws 1 and 2 have extensions beyond their pivot pin 3 so as to provide a scissors-like structure. The jaw 35 1 is terminally folded upon itself upon a portion of its length to provide a finger rest 13 by means of which it can be actuated. The extremity of the companion jaw 2 is formed with a hole through which passes the pin 7 40 carrying a rocker 12 made up of a metal plate folded upon itself in U shape and so formed at its free end as to provide a pawl 8 which can come into engagement with ratchet teeth or serrations 5 formed on the 45 middle bulging part of the companion jaw 1 adjacent the pivot 3. For laterally guiding the pawl 8; the metal guard 14 is riveted externally of the jaw 2 so as to protrude beyond the teeth or serrations 5 and oblige 50 the pawl 8 to move exclusively between the jaw 2 and said guard 14.

It will be understood that without departing from the spirit and scope of the invention as will be set forth in the appended 55 claims, numerous minor constructional details might be modified. Thus for instance the wings 10 and 11 of the rocker in the embodiment illustrated in Figures 2 and 3 could be shaped otherwise as long as one of 60 them would be partly cut away as a pawl or like engaging member adapted to ensure

a locking contact in one direction with teeth, serrations or even a smooth curvilinear arresting surface on the edge of the companion jaw.

65

What I claim is:—

1. A clip for hermetically constringing and closing the open end of hair waving sachets comprising in combination a pair of flat arcuate jaws pivotally connected and so shaped as to innerly delineate a recess of varying area, the one jaw having one part folded upon itself into a finger piece and ratchet teeth on its outer curvature and the other jaw being fitted at its end opposite the pivot with a channelled rocker the outer part of which is formed as a finger rest whilst one of its wing portions is cut as a pawl for securely engaging the teeth on the companion jaw when inwardly swung and both wing portions have tongue-like extensions for guiding the mutual displacement of the jaws.

2. A clip for hermetically constringing and closing the open end of hair waving sachets comprising in combination a pair of flat arcuate jaws arranged in overlapping relation at one end and connected at said end by a pivot, the one jaw having an integral finger piece and ratchet teeth on its outer curvature having said pivot as a centre, and the companion jaw being fitted at its free end opposite the pivot with a channelled rocker the heel part of which is formed as a flat finger rest whilst its wing portions are cut away so as to provide a pawl for securely engaging the teeth on the companion jaw when inwardly swung and guiding tongues for precluding any relative sway of the jaws.

100

3. A clip for hermetically constringing and closing the open end of hair waving sachets comprising in combination a pair of flat jaws pivotally connected to each other intermediate their ends and having extensions to present a scissors-like structure, the one jaw being terminally folded upon itself adjacent one end into a finger-rest and formed on its arcuate bulging edge adjacent the pivotal connection with ratchet teeth, and the other jaw being fitted at its free end with a channelled rocker formed by a folded plate providing a finger-rest and cut away in pawl shape so as to securely engage the teeth on the companion jaw when inwardly swung, and a guard fixed on the last-named jaw for precluding any relative sway of the jaws.
